UNITED STATES PATENT OFFICE.

GEORGE S. BENNETT, OF SAN FRANCISCO, CALIFORNIA.

VACUUM-CLEANER.

1,102,130.

Specification of Letters Patent. Patented June 30, 1914.

Application filed May 22, 1909. Serial No. 497,627.

To all whom it may concern:

Be it known that I, GEORGE S. BENNETT, a citizen of the United States, residing at San Francisco, in the county of San Francisco and State of California, have invented a new and useful Vacuum-Cleaner, of which the following is a specification in such full and clear terms as will enable those skilled in the art to construct and use the same.

10 This invention relates to a vacuum cleaner used for the purpose of taking up the dust from floors, and household furnishings of all kinds.

An object of the invention is to produce a 15 wheeled machine which may be operated over a floor without a hose tool for the purpose of picking up the dust from clear floors, while a hose may be attached to the machine for cleaning furniture, curtains or inaccessible places.

In the drawings, in which the same numeral of reference is applied to the same portion throughout the several views, Figure 1 is a plan view of the cleaner, Fig. 2 is a side 25 elevation of the cleaner, Fig. 3 is a side elevation of the cleaner showing the casing which covers the motor, Fig. 4 is a vertical sectional view of the cleaning tool carried by the fan on the line 4—4 of Fig. 1, Fig. 5 is a view of the valve used for changing 30 the air current from the tool on the machine to a tool on a hose which may be attached to the fan casing. Fig. 6 is a vertical section through the handle, the fan case and nozzle 35 of the machine, the motor not being shown in section.

The numeral 1 is applied to the frame to which the motor M is secured, said frame being U shaped and being secured to the casing of the fan by means of bolts 2. The frame of the motor has holes drilled in it into which the screws 3 are secured, and which screws hold the U frame to the motor body.

45 The casing 4 of the fan is of a common form, the air discharge 5 being toward the motor side of the fan, said discharge having the corners cut off to provide projections whereby a dust collecting sack may be secured to the fan casing and be prevented from being blown off, a string being tied around the sack and the discharge.

A tubular handle 6 is secured to the frame 1 said handle being in two parts, one, 7 sliding into the other 8, a threaded socket 9 being provided for the purpose of securing

the portion 7 in any desired position. The handle is adjustable in length by sliding the tube 7 into or out of the tube 8, and is secured in any given position by tightening 60 the socket 9 which causes the tube 8 to frictionally engage the tube 7 so tightly as to prevent any relative motion of the two tubes, enough of the inner portion 7 always being left in the portion 8 to insure the proper 65 securing of the parts. The handle is also used for the purpose of leading in the supply wires 10 for the motor.

The front plate 11 of the fan-casing has a flanged central opening formed by a tubular 70 extension 11' of the front plate and within which is mounted a rotary hollow tubular member 12, the walls of said member co-operating with the flanged opening in the plate 11, to form a chamber intermediate 75 the fan-casing and the suction tool. The inner end 14 of said tubular member is cut away, as shown at 14', and constitutes a rotary valve so that when it is turned to register with the duct 13, the tool is in communication with the intermediate chamber leading to the fan-casing and when the valve is turned through an angle of 180° into the reverse position, communication with the duct 13 leading to the tool is cut 80 off. When said rotary member 12 is turned as just mentioned, the cap 16 may be removed, thereby opening the outer end 15 of the tubular member which then forms an inlet pipe which may be connected as desired 85 and through which the air will be drawn by the fan. When it is desired to use the tool on the fan casing, the valve 12 is rotated so that the recess 14' is below and adjacent the duct 13, the cap 16 being placed 90 over the end of the pipe 15 to cause all the air to enter the fan through the tool on the casing.

The duct 13 in the fan casing plate 11 leads down nearly to the bottom of said 100 plate, a projection on said plate having a seat 17 which is a little more than semi-cylindrical. This seat 17 is adapted to receive the tool 18, a partly cylindrical portion thereof sliding into the seat 17, and 105 since it is substantially the same in size it makes a close joint with said seat, whereby the air will all be compelled to pass into the fan casing through the tool 18. The tool is held in place in the seat 17 by means 110 of a plate 19 at each end of said seat the plates being secured in position after the

tool has been placed in said seat. In the sectional view it will be noted that the end of the tool 18 is provided with a hole 18', the object of said hole being to afford means whereby the short axles 21 on which the wheels 22 turn may be secured to the tool, the axis of the tool and the axis of the wheels being the same. The movement of the tool in the seat above described is sufficient for all ordinary angles at which the handle will be held by a person when using the cleaner, and since the handle 6 is adjustable the amount of necessary movement of the tool is reduced since a short person will use the handle shorter than tall persons and vice versa.

It will be noted that if the mouth of the tool sat down squarely on the carpet all sides of it would touch the carpet and the only way the air could reach the fan would be through the carpet. While this would clean the carpet it is necessary to provide means whereby more air may pass to the fan than could pass through the carpet, and this means is a removable blade 23, said blade being wide enough to project below the lower edge of the cleaning tool a small distance. The blade is placed in a groove in the tool, a spring 24 being provided to bear on the tool at each end thereof whereby the blade may be removed or replaced at will. The blade has another function in that it agitates the nap of the carpet as the cleaner is moved forward. The result of this action is that small quantities of dust are thus forcibly projected from the carpet surface and the air at once takes them into the fan casing and to the dust collecting bag.

In order that the motor may not be exposed to view and liable to injury by the collection of dust in its various parts a casing C is slipped over the handle said casing being secured to the frame which supports the motor in any suitable manner.

Having thus described my invention what I claim as new and desire to secure by Letters Patent of the United States is as follows:

1. In a vacuum cleaner, a frame, a motor secured in said frame, a fan driven by the motor and also secured in the frame, a movable suction tool secured to a removable plate in front of the fan, wheels supporting the fan and having substantially the same axis as the movable tool, a blade carried by said tool projecting below the face thereof and adapted to disturb the nap of a carpet as the tool is passed thereover, and a handle secured to said frame and which is adapted to hold said frame in an inclined position when held in the hand, as set forth.

2. In a vacuum cleaner, a frame, a motor secured to the frame, a fan secured to the motor shaft and driven by the motor, a removable plate on the front of the fan cas-

ing and having an eye at its center and a duct leading nearly to the bottom of the plate, a tool movably secured to the plate adjacent the lower end of said duct, a handle secured to the frame adapted to tilt the motor and fan into the desired angle with relation to the floor when held by a person and a pair of wheels in front of said fan upon which the fan and motor are supported when the handle is raised off the floor, as set forth.

3. A vacuum cleaner, comprising a casing, a fan revolvably mounted therein, said casing having an opening in axial alinement with said fan, a removable cover plate for the opening secured to the casing, a suction tool secured to and projecting below said plate, a frame secured to said casing, a motor carried by said frame and connected to said fan, and a handle operatively secured to the cleaner.

4. In a vacuum cleaner, a fan casing, a pivoted suction tool secured to the lower portion of said fan casing, wheels to support said fan casing, said wheels being journaled upon the same axis with said tool between the mouth of said tool and said fan casing, a fan in said casing, a motor secured to said fan, a frame to which said motor is secured, and a handle secured to said frame and extending away from said fan casing, substantially as set forth.

5. A vacuum cleaner, comprising a casing, a fan revolvably mounted therein, said casing having an opening in axial alinement with said fan, a cover plate extending over said opening and removably secured to said casing, said plate being provided with a tubular extension forming a recess or chamber in direct axial alinement with said fan and a separable closure member for said chamber, a suction tool carried by said plate, said tubular extension being provided with a port connecting said tool and said chamber, and a valve in said chamber controlling said port.

6. In a vacuum cleaner, a fan casing having an inlet port and an exhaust port, a fan operative within the casing, a motor directly secured to said fan, means for supporting said motor in said casing, a removable plate secured to the inlet side of the casing, said plate being provided with a valve chamber in communication with said fan casing, a suction tool carried by said plate and communicating with said casing through said chamber, a tubular valve in said chamber for controlling the communication between the tool and the casing, and having a removable closure at the outer end of said chamber adapted to be removed when the valve is in a closed position to permit said valve to serve as an inlet pipe.

7. In a vacuum cleaner, a fan casing, a fan rotatable within said casing, a motor

mounted upon said casing, a suction tool secured to said casing and out of alinement with the axis of rotation of said fan and motor, a valve chamber intermediate said fan casing and said suction tool and in axial alinement with said fan and forming a communication therebetween, a tubular valve located in said chamber and controlling said means of communication, and a removable closure cap for said chamber adapted to be removed when the valve is in closed position.

8. A vacuum cleaner, comprising a casing, a fan revolvably mounted therein, said casing having an opening in axial alinement with said fan, a cover plate extending over said opening and removably secured to said casing, said plate being provided with a tubular extension forming a recess or chamber and having a removable cap or closure and a suction tool carried by said plate communicating with said chamber.

9. A vacuum cleaner, comprising a casing, a fan revolvably mounted therein, a motor secured to said casing, said casing having an opening in axial alinement with said fan, 25 a suction tool carried by said casing and out of alinement with the axis of rotation of said fan, said casing having a tubular extension, said tool being in communication with the tubular extension, said extension 30 being provided with an opening in substantial alinement with said fan, a removable closure for said opening, and means for closing the communication through said tool.

In testimony whereof I have set my hand 35 this 5th day of May A. D. 1909, in the presence of the two subscribed witnesses.

G. S. BENNETT.
